US00D620068S

(12) **United States Design Patent**
Cink et al.

(10) **Patent No.:** **US D620,068 S**
(45) **Date of Patent:** ** *Jul. 20, 2010

(54) **LIVE TRAP FOR TRAPPING RODENTS**

(75) Inventors: **James H. Cink**, Ballwin, MO (US); **Jonathan D. Berger**, St. Louis, MO (US); **Brian James Mann**, Wildwood, MO (US); **Edward Francis Marshall**, Lansing, MO (US); **Henry Wayne Moran**, Ballwin, MO (US); **James David Poling**, Clarkson Valley, MO (US)

(73) Assignee: **BASF Corporation**, Florham Park, NJ (US)

(**) Term: **14 Years**

(21) Appl. No.: **29/343,948**

(22) Filed: **Sep. 22, 2009**

(51) LOC (9) Cl. **22-06**

(52) U.S. Cl. **D22/119**

(58) Field of Classification Search D22/119-124;
43/58, 60-61, 68, 76, 81, 112-114, 124,
43/131, 132.1; D23/335, 342

(57) **CLAIM**

The ornamental design for a live trap for trapping rodents, as shown and described.

DESCRIPTION

FIG. 1 is a front perspective of a live trap for trapping rodents showing a base and a lid according to our new design;

FIG. 2 is a front elevational view thereof;

FIG. 3 is a top plan view thereof;

FIG. 4 is a right side elevational view thereof;

FIG. 5 is a left side elevational view thereof;

FIG. 6 is a bottom plan view thereof;

FIG. 7 is a rear elevational view thereof;

FIG. 8 is a front perspective of live trap for trapping rodents shown in FIG. 1 with the lid removed;

FIG. 9 is a front elevational view thereof;

FIG. 10 is a top plan view thereof;

FIG. 11 is a right side elevational view thereof;

FIG. 12 is a left side elevational view thereof;

FIG. 13 is a bottom plan view thereof; and,

FIG. 14 is a rear elevation view thereof.

1 Claim, 14 Drawing Sheets
